UNITED STATES PATENT OFFICE.

ERNST HERMANN RIESENFIELD, OF FREIBURG, GERMANY, ASSIGNOR, BY MESNE ASSIGNMENTS, TO THE CHEMICAL FOUNDATION, INC., A CORPORATION OF DELAWARE.

PROCESS OF MAKING THE CHLORINATED PRODUCTS OF METHANE.

Application filed October 4, 1918. Serial No. 256,929.

To all whom it may concern:

Be it known that I, ERNST HERMANN RIESENFIELD, a subject of the German Emperor, residing at Freiburg, Germany, have 5 invented certain and useful Improvements in Processes of Making the Chlorinated Products of Methane (for which I have made application in Germany, August 11, 1917); and I do hereby declare the following to be 10 a full, clear, and exact description of the invention, such as will enable others skilled in the art to which it appertains to make and use the same.

15

1. The process.

It is known that the various chlorinated products of methane or natural gas may be obtained by exposing a mixture of chlorine 20 and methane to the light, and it is also known that to avoid explosions it is advantageous to increase the intensity of the light to which the mixture is exposed by degrees (see German Patent No. 222919). It is also known 25 that these measures alone do not suffice for the production of the chlorinated products on a commercial scale. Even if the reaction is hastened by the accelerating effect of ordinary indoor temperature it proceeds too 30 slowly for commercial purposes. An obvious expedient therefore is to make use of heat as a means for accelerating the reaction. This invention forms the subject matter of 35 the Austrian Patent No. 63523. But in this patent it is not said how the explosion which, as set forth in the German Patent No. 222919 sometimes occurs "suddenly and without any ascertainable reason," and which renders the manufacturing process exceedingly dangerous. 40 Such explosions must occur from time to time, if no special measures are taken to prevent them. They often lead to the destruction of the entire manufacturing plant, or, at the least, to a breakdown, and thus considerably increase the 45 cost of manufacture. Even the "increasing of the intensity of the light by degrees" proposed in the German Patent No. 222919 is not a sure means of preventing explosions, 50 because a sudden exposure to light is only one of the numerous causes of explosions. It must, however, be acknowledged that by this measure alone a frequent cause of explosion is obviated.

The discovery of another cause of explosion has now been made and by its being consciously prevented a further increase in the safety of the commercial plant has been achieved. The newly discovered cause consists in fluctuations of pressure. The prevention of these fluctuations is the object of this invention. It has been found that the pressure waves originating in mixtures of chlorine and methane are particularly liable to change into explosion waves. It is true 65 that it is not peculiar to the manufacturing process that fluctuations of pressure must arise in it in any case. But as long as these are not prevented with forethought they will occasionally arise of themselves in the 70 following instances:

1. By the sudden turning on and off of the gas at the beginning and interruption of the process,

2. By the sudden turning on and off of the light, in consequence of which the expansion caused by the heat of radiation and by the heat of reaction (or the sudden contraction caused by the opposite process) gives rise to a secondary pressure wave,

3. By the sudden starting and stopping of the cooling in the condensation room. An explosion was once observed in connection with this manipulation, which was due to the pressure wave traveling back into the 85 reaction chambers.

The method of obviating fluctuations of pressure consists in providing means for preventing a sudden turning on and off of gas currents, of the light, and of the cooling 90 devices. These devices are known in themselves. The invention consists in installing them in the manufacturing plant and in making the known method of producing chlorinated products of methane safer and 95 thus cheaper by preventing consciously, and with forethought, sudden fluctuations of pressure.

II. The plant.

The entire plant consists of three units, viz:

- a, the reaction chambers,
- b, the absorption unit,
- c, the condensing unit.

a. The reaction chambers.

The reaction chambers consist of systems

100

105

of pipes or chambers through which the gases (chlorine and methane or natural gas) pass after being thoroughly mixed. As far as the process is concerned it is of no consequence whether the mixing of the chlorine and methane takes place in a special room or pipe before entering the first system of chambers or in the first of these chambers. It also makes no difference which of the known commercial equipments are used for thoroughly mixing the gases, or whether any of these equipments is altered in any special manner to accomplish the desired result. The only point of importance is that the gases are completely mixed and that devices are provided (e. g. regulating cocks) by which the speeds of flow of the chlorine and methane upon entering the mixing chamber may be separately regulated and sudden fluctuations of pressure prevented. If artificial light, say a mercury vapor lamp, is installed in the interior of the reaction chambers, the reaction chambers may consist of opaque material, e. g. earthenware. If the illuminating equipment is outside the chambers or if daylight is employed, one or several of the walls of the chambers must be made of glass or some other material that is transparent to the kind of light used as an agent for accelerating the reaction. Devices must be installed by which a sudden turning on and off of the light and a sudden change of the temperature of the chamber is prevented. Furthermore the chambers must be equipped with escape valves sufficient in number and cross section, and these valves must act automatically on a sudden rise of pressure, so as to allow a sufficient quantity of the gases to escape quickly.

b. The absorption unit.

The absorption of the liquid reaction products methylene chloride, chloroform and carbon tetrachloride, and of the hydrochloric acid which is simultaneously formed, is accomplished by a unit that is designed on lines similar to those of the turill system customary in hydrochloric acid works.

The absorption equipment is provided with the usual preliminary cooling devices. Devices are installed which ensure a gradual turning on said and off of the cooling water. Water is supplied in the usual way to the earthenware turill devices, the water absorbing the hydrochloric acid. As the other products are insoluble in water and hydrochloric acid, and as they are heavier than these liquids, they settle in the turill devices beneath the hydrous layer. The separation of the hydrous and anhydrous layers may be effected by tapping them off

at different heights from the turill devices, or it may be effected in special vessels after the settling of the liquid mixture. The counter current principle will be preferably adopted here, similarly as in the known process for absorbing hydrochloric acid. 70

c. The condensing unit.

The gas which escapes from the absorption unit contains methyl chloride and small quantities of unliquefied methylene chloride in addition to methane. The former are condensed by causing the gases to pass through a compression pump in which the gases are compressed to about 20 atmospheres. At this pressure the most volatile reaction product, viz. the methyl chloride, is condensed at ordinary indoor temperature and may be retained in steel bottles, for example. The final and only residual gas is excess of methane. This may either escape or it may be subjected anew to the manufacturing process.

In the accompanying drawing there is represented, diagrammatically, an illustrative embodiment of an apparatus in which the objects of the invention may be attained and in which the reactions may be carried out, and therein are shown cylinders containing chlorine and methane, these cylinders being connected by means of suitable conduits provided with regulatory devices by means of which the chlorine and methane independently flow into a reaction chamber, which may be of rectangular construction, having a suitable source of light within, such as an incandescent electric lamp or a mercury vapor lamp, the light source having the current led to it through a rheostat of desired range. The reaction chamber further is equipped with safety valves having a capacity such that when the pressure of the gases shall exceed a certain definite limit, the excess gases may be quickly removed. The reaction having taken place within the reaction chamber, the products thereof are led therefrom through an exit conduit to an absorption train which may consist of a series of Woulfe bottles or turills, each bottle being connected with a reservoir by means of a pipe having a valve therein, and the last of said bottles being connected with a compressor in which the methane and any uncondensed chlorides of methane are separated. The chlorides, which are condensed, pass from the compressor through a valved pipe to a reservoir, whereas the methane escapes through a suitable outlet.

In order to provide a desired cooling medium, a liquid which shall be adapted to this purpose is led upon the counter-current principle through the Woulfe bottles, entering the bottle nearest the compressor

through a pipe provided with a regulatory device. The regulatory devices, or valves, which are used throughout the apparatus are such as will enable the operator to start or to stop the reaction gradually.

III. Process of making methyl chloride.

If the principal product to be obtained is methyl chloride, the procedure to be observed is that the speed of flow of chlorine and methane is such that in the reaction each part of the chlorine reacts with an equal part of methane. Since, if this condition is fulfilled, only small traces of carbon tetrachloride, very little chloroform and only small quantities of methylene chloride are formed, the absorbing equipment required for this process may be small in comparison with the condensing plant. Thus a small turill plant and a large compression pump are required.

IV. Process of making chloroform.

If the chief product to be prepared is chloroform, three parts of chlorine are allowed to enter into reaction with each part of methane. This renders a larger turill plant and a smaller compression pump necessary.

V. Process of producing carbon tetrachloride.

If the principal product desired is carbon tetrachloride, the speed of flow of the chlorine and methane must be regulated in such manner that four parts of chlorine enter into reaction with each part of methane. Besides carbon tetrachloride, liquid products will then be formed, chiefly chloroform and a small quantity of methyl chloride. In this case the absorption unit will be made large and the condensing unit small.

VI. Examples.

As an example of the quantities of reaction products obtained it may be mentioned that, if one part of chlorine enters into re-

action with one part of methane, the following quantities result:

Methyl chloride	80%	55
Methylene chloride (CH_2Cl_2)	10%	
Chloroform	6%	
Carbon tetrachloride (CCl_4)	2%	
Perchlorethane	2%	

If about one part of methane enters into reaction with 3-5 parts of chlorine, the quantities obtained are:

Methyl chloride	5%	
Methylene chloride	7%	
Chloroform	36%	65
Carbon tetrachloride	42%	
Perchlorethane	10%	

I claim.

1. In a system for the production of chlorinated products of methane from a mixture of chlorine and methane, the improvement which consists in installing devices which prevent a sudden release and stoppage of the flow of gas to and from reaction chambers.

2. In a system for the production of chlorinated products of methane from a mixture of chlorine and methane, the improvement which consists in installing devices which prevent a sudden starting and stopping of the cooling medium.

3. In a system for the production of chlorinated products of methane from a mixture of chlorine and methane, the improvement which consists in installing devices which prevent a sudden turning on and off of the source of actinic energy.

4. In a system for the production of chlorinated products of methane from a mixture of chlorine and methane, the improvement which consists in installing devices which control the flow of gas, the flow of the cooling medium and the source of actinic energy, whereby a sudden release and stoppage of the said factors are prevented.

In testimony whereof I affix my signature, in presence of two witnesses.

ERNST HERMANN RIESENFIELD.
